[57] CLAIM

The ornamental design for a child's hat, as shown and described.

DESCRIPTION

FIG. 1 is a perspective view of my new design for a child's hat with fastening cords tied to a wearer, the wearer shown in dotted lines;

FIG. 2 is a perspective view thereof, the fastening cords
being untied;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.
